(57) **CLAIM**

We claim the ornamental design for the overlay, substantially as shown and described.

DESCRIPTION

FIG. 1 is a top perspective view of an overlay, according to a first embodiment;

FIG. 2 is a bottom perspective view of the overlay, according to the first embodiment;

FIG. 3 is a top plan view of the overlay, according to the first embodiment;

FIG. 4 is a side elevational view of the overlay, according to the first embodiment, where the opposite side elevational view is a mirror image thereof;

FIG. 5 is a bottom plan view of the overlay, according to the first embodiment;

FIG. 6 is a top perspective view of the overlay in a folded configuration, according to the first embodiment;

FIG. 7 is a top perspective view of an overlay, according to a second embodiment;

FIG. 8 is a bottom perspective view of the overlay, according to the second embodiment;

FIG. 9 is a top plan view of the overlay, according to the second embodiment;

FIG. 10 is a side elevational view of the overlay, according to the second embodiment, where the opposite side elevational view is a mirror image thereof;

FIG. 11 is a bottom plan view of the overlay, according to the second embodiment; and,

FIG. 12 is a top perspective view of the overlay in a folded configuration, according to the second embodiment.

The evenly dashed broken lines of the various embodiments of the overlay are directed to environment and are for illustrative purposes only; the evenly dashed broken lines form no part of the claimed design.
